UNITED STATES PATENT OFFICE.

WILLIS N. GRAVES, OF ST. LOUIS, MISSOURI, ASSIGNOR TO THE HYDRAULIC PRESS BRICK COMPANY, OF SAME PLACE.

BRICK-KILN.

SPECIFICATION forming part of Letters Patent No. 616,415, dated December 20, 1898.

Application filed July 18, 1898. Serial No. 686,232. (No model.)

To all whom it may concern:

Be it known that I, WILLIS N. GRAVES, a citizen of the United States, residing at the city of St. Louis, in the State of Missouri, have invented certain new and useful Improvements in Brick-Kilns, of which the following is a full, clear, and exact description, reference being had to the accompanying drawings, forming part of this specification.

10 My present invention relates to certain improvements in what are known as "continuous brick-kilns."

15 My invention consists in features of novelty hereinafter fully described, and pointed out in the claims.

Figure I is a top or plan view of my improved kiln. Fig. II is a view part in elevation and part in section taken on line II II, Fig. I. Fig. III is an enlarged detail top view. Fig. IV is an enlarged vertical transverse section taken on line IV IV, Fig. III, looking in the direction of the arrow that crosses the section-line. Fig. V is an enlarged detail vertical section showing part of the longitudinal partition and part of one of the portable flues. Fig. VI is an enlarged detail vertical section taken on line VI VI, Fig. III. Fig. VII is a top view of one of the sand-boxes of the caps or valves. Fig. VIII is an enlarged transverse section of one of the portable air-flues, the section being taken on line VIII VIII, Fig. IV. Fig. IX is an enlarged vertical section of one of the hoods of the central flue of the kiln. Fig. X is an enlarged detail horizontal section taken through the lower longitudinal flues at the chimney end of the kiln, the location of the chimney being shown in dotted lines and the fan being shown in plan view.

40 The kilns of the class to which my invention relates have a number of chambers in which the bricks are burned. I have shown a kiln with eighteen of these chambers and have marked them from 1 to 18, consecutively. The number of chambers may, however, be varied. The chambers are separated by a longitudinal partition 19, in which is formed a flue 20, (see Fig. IV,) from which extend short vertical flues 20^a. (See Fig. V 45 and dotted lines, Fig. IV.) The chambers

have solid floors, except at one side of each chamber there is a grate 21, and beneath each grate there is a flue 22, the flues running transversely of the kiln, those on one side of the kiln being separated from those on the other side by the partition 19. The outer ends of the flues 22 communicate, as shown in Fig. IV, with longitudinal side flues 23 24, there being two of these flues on each side of the kiln. The flues 24 extend to a chimney 60 or uptake 25, as shown in Fig. X and by dotted lines, Fig. I, while the flues 23 extend to a suction-fan 27, and they may be provided with branches 28, (see Fig. X and dotted lines, Fig. I,) extending to the chimney and 65 provided with valves 29. The communication between the flues 22 and the flues 23 and 24 is controlled by valves 23^a and 24^a, provided with stems 30, by which they can be readily moved.

70 31 represents destructible partitions (preferably of paper) which form the only separation between the different chambers of the kiln. These partitions resist the passage of the air from one chamber to another until 75 they are burned out, and then the separation between the chambers thus having the partitions destroyed disappears. Each chamber has an individual furnace 32 for the preliminary work of drying the bricks in the respective chambers.

75 33 represents vertical flues formed in the side walls of the kiln and which communicate with the individual furnaces 32. (See Figs. II and IV.)

80 85 34 represents portable air-flues open at the bottom except from A to B (see Fig. V) and having necks 35, adapted to fit over the upper ends of the flues 20^a and 33, the flues being preferably provided with sand boxes or rings 36 to receive the necks of the flues, as shown in Fig. V.

In placing the bricks in the chambers they are laid so as to form a number of vertical spaces or openings in each chamber, one of 95 which is shown at 37, Fig. VI. When the chambers are filled almost to the top with green bricks, there are one or more layers of burned bricks 38 placed on top of the green bricks, (see Fig. VI,) and where the openings 100

37 in the mass of green bricks occur rings 39 are placed, the ring being formed with sand-chambers 40, adapted to receive caps 41. A number of these rings are shown in Fig. III, 5 and an enlarged view of one of them is shown in Fig. VI.

When a chamber has been filled and covered, as referred to, a fire is started in its individual furnace 32 to remove the mechanical 10 water from the bricks. In removing this mechanical water it is necessary that it should be done without the use of fuel that contains sulfur, or otherwise the bricks will be discolored, and for this reason the individual 15 furnaces are provided in which coke, gas, or some such form of fuel is used. During this preliminary process of burning the bricks the portable flues 34 are placed with their necks 35 over the flues 33, the open bottom of the 20 flues being set over part of the rings 39, as shown in Fig. III, and as shown also in Fig. I at the chambers 11, 12, 13, and 14, the heat being thus conducted from the individual furnaces through the troughs, from where it 25 passes into the chambers, and passing down through the green bricks enters the flues 23, (the valves 23^a of these chambers being open,) the draft for this circulation being produced by the suction-fan 27, which affords a strong 30 draft that may be regulated to suit the conditions. In case of accident to the fan or the machinery that drives it the valves 29 may be opened and the draft for this preliminary work be produced by the chimney or uptake. 35 When the mechanical water is thus removed from the bricks, ordinary soft coal is dropped into the openings 37 by removing the caps 41, and when the openings are filled the caps are replaced and the coal burns in numerous 40 places through the mass of bricks in each chamber, the draft being created by the chimney through the flues 22 and 24, (the valves 23^a having been closed and the valves 24^a opened,) the chimney now being utilized to 45 produce the draft during the main stage of the burning of the bricks and when fuel is being used that produces a considerable amount of smoke. During this principal stage of the burning of the bricks the portable flues 34 50 are not used, but are moved over to another chamber, where the preliminary burning referred to is going on.

During the preliminary burning, while the mechanical water is being driven off the 55 structible partitions keep the chambers separated; but after this preliminary burning is accomplished the partitions become consumed and the chambers become as one chamber.

Referring to Fig. I, by way of illustrating 60 the operation of the kiln, it may be assumed that chamber 15 is empty, while the chambers 16, 17, 18, and 1 have all been burned, and 16, 17, and 18 may have been emptied, while chamber 1 is still too hot to be emptied. In 65 chambers 14, 13, 12, and 11 the mechanical water is being driven out by heat from the individual furnaces. In chambers 10 and 9

the mechanical water has been removed and these chambers are receiving surplus heat from chambers 2, 3, and 4, this heat being 70 passed to the chambers 10 and 9 by means of the portable flues being placed over some of the rings 39, the necks of the flues being placed over the flues 20^a, so that the heat passes from chambers 2, 3, and 4 into the flue 75 20, and from thence into the chambers 10 and 9 through the portable flues (shown in Fig. I) over the chambers 10 and 9. This hot air, passing down through the bricks in chambers 10 and 9, enters the flues 23 under the 80 draft of the suction-fan. The bricks in chambers 8 and 7 are being burned by hot air and gases passing to them from the chambers 6 and 5, the paper partitions between the chambers 6, 7, and 8 having been burned out. At 85 this time the coal in chambers 8 and 7 has not been ignited. In chambers 6 and 5 the bricks are being burned by the coal contained in the openings 37. In the chambers 4, 3, and 2 the bricks have been burned and the 90 fires in the openings 37 extinguished. Part of the hot air is passed from the chambers 4, 3, and 2 at this time through the bricks in chambers 5, 6, 7, and 8, (supplying oxygen to the fuel in chambers 6 and 5,) and part also 95 passes, as stated, through the portable flues and the flue 20 to the chambers 9 and 10. This continuous operation is kept up by a fresh chamber being filled each day, chamber 15 being filled one day and the portable 100 flues from chamber 11 being moved over to chamber 15. The next day chamber 16 would be filled and the portable flues from chamber 12 be moved to chamber 16, and the portable flues at the right of Fig. I are advanced in 105 like manner from one chamber to another.

To provide sufficient room at the ends of the partitions 19 for the portable flues to connect with the flue 20 I locate hoods 43 on the top of the kiln, which communicate, as shown in Fig. IX, with the flue 20, and in these hoods openings are formed to receive the necks of the portable flues used for the chambers 2, 3, and 4 and for the chambers 11, 12, and 13.

I claim as my invention—

1. In a continuous brick-kiln, the combination of a series of chambers having individual furnaces and having individual flues covered by grates, a central partition provided with 110 flues, a pair of side flues communicating with a chimney, a pair of side flues communicating with a suction-fan, and portable flues for forming communication between said chambers and the central and side flues, substantially as set forth.

2. In a continuous brick-kiln, the combination of a series of chambers having individual furnaces, a pair of side flues communicating with a suction-fan and a pair of side flues 130 communicating with a chimney, valved communication between the bottoms of said chambers and said flues, a central partition having flues, and portable flues adapted to form com-

munication between said chambers and said central flues, substantially as set forth.

3. In a continuous brick-kiln, the combination of a series of chambers having individual furnaces provided with vertical flues located in the side walls of the kiln, horizontal flues located in the side walls of the kiln and communicating with means for producing a draft, a central partition provided with flues, and portable flues adapted to form a communication between said chambers and said central and vertical side flues, substantially as set forth.

4. In a continuous brick-kiln, the combination of a series of chambers having individual furnaces provided with vertical flues located in the side walls of the kiln, portable flues adapted to form a communication between said chambers and said vertical flues, valved side-flues forming a communication between said chambers and a suction-fan whereby a draft is produced for the drying of the bricks, and side flues forming a communication be-

tween said chambers and a chimney whereby a draft is produced for the burning of the 25 bricks, substantially as set forth.

5. In a continuous brick-kiln, the combination of a series of chambers separated by destructible partitions and having individual furnaces provided with vertical flues located 30 in the side walls of the kiln, a central partition provided with flues and hoods at the ends thereof, portable flues adapted to form communications between the chambers and said central flues and between the chambers and 35 said vertical side flues, valved horizontal side flues forming a communication between the chambers and a suction-fan, and valved side flues forming a communication between the chambers and a chimney, substantially as set 40 forth.

WILLIS N. GRAVES.
